SURGICAL TRUSS STRUCTURE

John A. Chesterman, Philadelphia, Pa., assignor
to Chesterman Leeland Company, Philadelphia,
Pa., a corporation of Pennsylvania

Application February 12, 1941, Serial No. 378,671

6 Claims. (Cl. 128—99)

This invention relates to surgical trusses such as are used for the care and treatment of abdominal hernias. The present invention relates more particularly to the type of truss which employs a longitudinally curved body-embracing spring for holding the truss pad in position over the area of the hernia.

It is common practice to encase the truss spring between two strips of leather or other suitable material and to stitch the two covering strips together outside and parallel to the opposite longitudinal marginal edges, respectively, of the spring.

In other instances, it has been common practice to secure a strip of felt to the leather strip on the inside of the curved spring by the same stitching which holds the two covering strips together around the spring.

The two exposed rows of stitches which secure the marginal edges of the spring-covering strips and the cushion together are objectionable, in that they become soiled and cannot be readily cleaned. Furthermore, these stitches become unsanitary and odoriferous as a result of becoming saturated with perspiration, while also causes the sewing thread to rot, leaving the two covering strips separate to admit the perspiration to the spring, causing the spring to rust.

The object of the present invention is to provide a sanitary spring sheathing employing a single row of stitches hidden from view and protected against the ravages of perspiration.

In the accompanying drawings:

Fig. 1 is a perspective view of one form of spring sheathing and cushion made in accordance with the principles of the present invention;

Fig. 2 is a section taken on the line 2—2, Fig. 1;

Fig. 3 is a perspective view showing a modified form of cushion;

Fig. 4 is a section taken on the line 4—4, Fig. 3;

Fig. 5 is a perspective view illustrating the invention as applied to a double-spring truss; and

Fig. 6 is a section taken on the line 6—6, Fig. 5.

As shown in Fig. 2, the truss spring 1 is of the flat ribbon type, having a rectangular cross-section. The spring 1 is curved longitudinally to encircle partially the body of the person wearing the truss. The curved spring 1 is sheathed in a casing 2 composed of leather or other suitable material, which may be readily cleansed by wiping the damp cloth.

The sheathing or casing 2 is formed of a single strip of material folded transversely around the spring 1, as clearly shown in Fig. 2, to provide a plain outer face 3, edge faces 4 and 5, and inner

face portions 6 and 7. The inner face portions 6 and 7, at a median plane x—x between the upper and lower edges 4 and 5, are bent at right angles to the transverse plane of the spring 1, 5 in the form of inwardly projecting flanges 8 and 9, respectively, which lie in abutting relation to each other at the plane x—x.

The flanges 8 and 9 are held in abutting relation to each other by a single longitudinal row 10 of stitches 10, which extend from the truss pad supporting end 11 of the body-embracing structure A to the fastening-strap end 12 thereof.

The spring 1 extends through the casing 2, from the truss pad supporting end 11 of the body-embracing structure A, to a point approximately midway between the ends 11 and 12 of the structure, as indicated in dotted lines at 13 in Fig. 1.

On the inside curvature of the body-embracing structure A, is a cushion-forming strip 15, which 20 is composed of leather or other suitable material. The cushion strip 15 is in a single piece and is loosely folded transversely to provide a plain, smooth, inner surface 16 with smoothly rounded upper and lower edge curves 17 and 18.

25 The outer portions 19 and 20 of the cushion strip 15 bend inwardly, then outwardly, into contact with the flanges 8 and 9 and inner portions 6 and 7 of the sheathing casing 2, and are held in abutting contact with the flanges 8 and 9 by 30 the single row of stitches 10, which pass through the portions 19 and 20 of the cushion strip 15 and the flanges 8 and 9 of the spring-casing strip, in a plane parallel to the spring 1.

The cushion formed by the strip 15 is wider 35 than the casing 2 of the spring 1 and the looseness of the cushion strip, with respect to the spring casing, affords relative movement between the inner body contacting face 16 of the cushion and the spring 1, so that no chafing of the person's 40 skin will occur as a result of movement of the spring during any activities in which the person may be engaged.

A truss pad B is normally attached to a bracket 21, which is secured to the outside of the one end 45 11 of the body-embracing structure A, by screws 22 which pass through the spring casing 2 and enter threaded openings in the spring 1.

50 A strap C is secured in the end 12 of the body-embracing structure A by stitching 23, rivets or other suitable means. The strap C is inserted in the otherwise open end 12 of the cushion formed by the folded strip 15.

The strap C is provided apertures 24 for engagement with a post 25 projecting outwardly 55 from the truss pad bracket 21.

In Figs. 3 and 4, the cushion-forming leather strip 15 is replaced by a cushion-forming strip 15a composed of felt, rubber or other suitable material.

The outer face 26 of the strip 15a is adhesively secured to upwardly and downwardly extending continuations 8a and 9a, respectively, of the flanges 8 and 9 of the spring casing 2, shown in Figs. 1 and 2, with a single row of stitches 10a holding together the two marginal portions of the leather strip of which the spring sheathing 2a is composed.

It will be noted that, in Figs. 3 and 4, the spring sheathing or casing 2a fits the spring 1a loosely, to provide for relative lateral movement between the spring 1a and the inside body-contacting surface 16a of the cushion strip 15a.

In Figs. 5 and 6, the invention is shown as being applied to a truss of the double spring type.

Each spring, one of which is shown at 1b in Fig. 6, forms part of a body-embracing structure A², A³, respectively. Each body-embracing structure, in addition to the truss spring 1b, includes a spring sheathing 2b and a cushion-forming strip 15b of felt, rubber, etc., adhesively secured to the marginal portions 8b, 9b of the strip of leather, etc., of which the spring sheathing 2b is composed, and which are secured together by a single row of stitches 10b. In this instance, the sheathings 2b, 2b, fit the springs 1b rather snugly, as in some cases relative lateral movement between the springs and the cushions may not be desired. However, if such relative movement is desired, the casings 2b may be made to fit the springs 1b loosely, as in the case illustrated in Figs. 3 and 4.

In each of the instances noted above, the spring sheathing is composed of a single strip of material which is maintained in a tubular form, to encase the spring, by a single row of stitches which is hidden from view and protected from the deteriorating effects of perspiration by being deeply buried between the spring and the body-contacting cushion, midway between the upper and lower edges of each, it being noted that, under conditions of use, the inner face of the spring casing and the outer face of the cushion will be pressed together above and below the row of stitches and will exclude direct communication to the row of stitches from the exterior of the body-embracing structure as a whole.

I claim:

1. A surgical truss structure comprising a body-embracing spring, a body-contacting pad adjacent one side and extending along the length of said spring, a sheathing for said spring composed of a single strip of flexible material folded transversely about the spring along the length thereof, and a row of stitches securing marginal portions of the strip together between the spring and the pad.

2. A surgical truss structure comprising a body-embracing spring, a body-contacting pad adjacent one side and extending along the length of said spring, a sheathing for said spring composed of a single strip of flexible material folded transversely about the spring along the length thereof, and a row of stitches securing marginal portions of the strip together between the spring and the

pad substantially midway between the opposite longitudinal edges of the spring.

3. A surgical truss structure comprising a body-embracing spring of thin, flat cross-section, 5 a body-contacting pad adjacent one flat side and extending along the length of the spring, a sheathing composed of a single strip of flexible material folded transversely around the spring along the length thereof with marginal portions 10 of the strip bent at right angles to the plane of said flat side of the spring and abutting each other in a plane intermediate the opposite longitudinal edges of said flat side of the spring, and a row of stitches securing said abutting marginal portions of said strip together between the spring and the pad.

4. A surgical truss structure comprising a body-embracing spring of thin, flat cross-section, 20 a sheathing composed of a single strip of flexible material folded transversely around the spring along the length thereof with marginal portions of the strip projecting from the plane of one flat side of the spring in flat abutting relation to each other, a body-contacting pad composed of 25 a single strip of flexible material folded transversely to produce an hollow center in the pad along the length of the spring with marginal portions of the pad strip in flat abutting relation to the flat abutting marginal portions of 30 the sheathing strip, and a row of stitches passing through the flat abutting marginal portions of both the pad strip and the sheathing strip intermediate the spring and the hollow-centered pad.

5. A surgical truss structure comprising a body-embracing spring of thin, flat cross-section, 35 a sheathing composed of a single strip of flexible material folded transversely around the spring along the length thereof with marginal portions 40 of the strip bent backwardly upon adjacent portions of the strip adjacent one flat side of the spring, and with the bends of said marginal portions lying in abutting relation on a line intermediate the longitudinal edges of the spring, a 45 row of stitches passing through said abutting bends of said marginal portions of the strip, and a body-contacting pad extending along the length of the spring and secured to said backwardly bent portions of the strip.

6. A surgical truss structure comprising a body-embracing spring of thin, flat cross-section, 50 a sheathing extending along the length of the spring and composed of a single strip of flexible material folded transversely around the spring 55 with marginal portions of the strip bent backwardly upon adjacent portions of the strip adjacent one flat side of the spring, and with the bends of said marginal portions lying in abutting relation on a line intermediate the longitudinal edges of the spring, a row of stitches passing 60 through said abutting bends of said marginal portions of the strip, and a body-contacting pad extending along the length of the spring and composed of a strip of felt of greater width than 65 said spring adhesively secured to said backwardly bent portions of the strip and extending laterally beyond the longitudinal edges of the spring sheathing.

JOHN A. CHESTERMAN.
